UNITED STATES PATENT OFFICE.

JOHN ROGERS, OF NEW CANAAN, CONNECTICUT.

DESIGN FOR A GROUP OF STATUARY.

SPECIFICATION forming part of Design No. 17,363, dated May 31, 1887.

Application filed May 4, 1887. Serial No. 237,136. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawings, forming part thereof.

10 The group has marked on the front of the base "A Frolic at the Old Homestead." The central figure of the group is an old lady seated in a chair with her knitting in her hands. On her right is a man blindfolded with a hand-
15 kerchief over his eyes. He is bending forward, and with his left hand he is reaching in front of the old lady and trying to catch a young lady standing on her left, who is just escaping by stepping back and drawing her

skirts away from his hand, which she is eagerly 20 watching. Her right hand is on the back of the old lady's chair. A young man standing at the back of the chair is assisting the young lady to escape by helping her back with his left hand, while he flirts a handkerchief with 25 his right hand against the head of the blindfolded man to distract his attention from the girl.

I claim—

The design for a group of statuary herein 30 shown and described, representing an old lady, a blindfolded man, a girl he is trying to catch, and a man behind who is assisting her to escape.

JOHN ROGERS.

Witnesses:

C. B. ARNOLD,
WM. BRUSH.
